US00D674134S

(12) **United States Design Patent**
Carroll et al.

(10) **Patent No.:** US D674,134 S
(45) **Date of Patent:** ** Jan. 8, 2013

(54) **ORAL TOBACCO ARTICLE**

(75) Inventors: **Andrew Nathan Carroll**, Chester, VA (US); **Shannon Maxwell Black**, Richmond, VA (US); **Tommy C. Holland**, Midlothian, VA (US); **Jason Andrew Macko**, Richmond, VA (US); **Christopher Joseph DiNovi**, Rutherford, NJ, VA (US)

(73) Assignee: **U.S. Smokeless Tobacco Company LLC**, Richmond, VA (US)

(**) Term: **14 Years**

(21) Appl. No.: **29/380,742**

(22) Filed: **Dec. 10, 2010**

(51) LOC (9) Cl. **27-01**

(52) U.S. Cl. **D27/100**

(58) **Field of Classification Search** D27/100; D25/113; D21/499; D24/101, 103, 104; D9/721; D28/7, 8, 8.1, 8.2, 56, 57, 59, 63; D1/100, 105, 127, 128, 129, 199; D19/53

(57) **CLAIM**

The ornamental design for an oral tobacco article, substantially as shown and described.

DESCRIPTION

FIG. 1 is a perspective view of an oral tobacco article.

FIG. 2 is another perspective view of the oral tobacco article of FIG. 1.

FIG. 3 is a top view of the oral tobacco article of FIG. 1, the bottom view being a mirror image.

FIG. 4 is a front view of the oral tobacco article of FIG. 1, the rear view being a mirror image; and,

FIG. 5 is a left view of the oral tobacco article of FIG. 1, the right view being a mirror image.

The broken lines which define environmental structure of the claimed design form no part thereof.
